MEDAL

Mauro Bartoli, 39 Rue des Diables Bleus,
Nice, Alpes Maritimes, France

Filed Nov. 5, 1965, Ser. No. 88,012

Claims priority, application Great Britain Aug. 27, 1965

Term of patent 7 years

(Cl. D29—19)

FIG. 1 is a front elevational view of a medal showing my new design.

FIG. 2 is an edge elevation thereof.

The side opposite that shown in FIGURE 1 is substantially plain and unornamented.

I claim:

The ornamental design for a medal, as shown and described.
